JAR CLOSURE

Horace V. Williams, Philadelphia, Pa.

Application December 1, 1936, Serial No. 113,731

1 Claim. (Cl. 215—40)

The object of the invention is to provide a jar closure construction whereby jars of glass or similar material may be effectively sealed air tight; to provide a closure construction embodying a rubber gasket or sealing ring so arranged that the sealing ring will be compressed throughout in the sealing operation and not subjected to a pull or tension, as in conventional practice, which tends to open the pores of the material; and generally to provide a jar closure which is of simple form and susceptible of cheap manufacture.

With this object in view, the invention consists in a construction and combination of parts 15 of which a preferred embodiment is illustrated in the accompanying drawing, wherein:

Figure 1 is an elevational view of the invention, with certain parts broken away.

Figure 2 is a detail sectional view showing the mouth of the jar and cap attached with the parts in position prior to the application of a pressure 20 on the sealing ring.

Figure 3 is a view similar to Figure 2 but showing the relative position of the parts when the cap is in fully closed position.

It is preferable to have the jar 10 and the cap clamping ring 11 of the same diameter, and thus the mouth of the jar is formed by contracting the latter circumferentially, as indicated at 12, this contraction providing a neck portion 13 of which the upper edge is beveled on the outside, as indicated at 14, and similarly beveled on the inside, as indicated at 15, the angles of the bevels being uniform on opposite sides of a vertical line passing through the peak 16 of the neck.

The cap 17 is formed with a pendent annular flange 18 of an exterior diameter to be readily received within the neck 13 and exterior to the flange has a ledge portion 19 of which the under- 40 face is channeled, as indicated at 20, to provide synclined walls which, when the cap is in position on the jar, parallel the beveled edges 14 and 15 of the neck.

The cap 17 is recessed on its upper face adjacent its periphery to provide a seat for the in-turned flange 21 of the clamping ring 11 and the latter at the lower edge has inturned lugs 22 engageable with the ribs 23 with which the neck

is provided on its periphery. The ribs are formed with inclined under edges and are arranged around the neck in a circular series with the nose end of one materially spaced from the heel end of the next. Thus in applying the ring, the lugs 5 pass between adjacent ribs and on rotation of the ring they slide down the inclined under-faces of the rib and thus draw the cap down on the neck.

The sealing ring 16 is placed on the cap in surrounding relation to the flange 18 before the cap is applied and rests in the channel 20 but on the inclined wall of the latter next to the flange 18. Thus, when the cap is applied, the underface of the sealing ring rests on the beveled wall 15 and 15 when the clamping ring is rotated the material of the sealing ring is compressed, as shown in Figures 1 and 3. The sealing ring is at no time subjected to tension at any point. Rubber is naturally porous and its effectiveness as a sealing medium depends on its being subjected wholly to compression. The present invention provides such a use, the inner beveled edge 15 of the neck, the flange 18 and the channel 20 of the cap serving to so embrace the sealing ring that the material thereof is compressed solely as the cap is drawn down on the neck when the clamping ring is rotated.

The invention having been described, what is claimed as new and useful is:

A jar and closure therefor, the former having a neck of which the upper edge is beveled interiorly and exteriorly and the latter channeled to provide walls paralleling said beveled edges when the closure is attached, and an elastic sealing 35 ring seated upon the inner beveled edge and of a width corresponding to the width of said edge, the closure having an annular pendent flange on the undersurface of an exterior diameter corresponding to the interior diameter of the neck, and 40 means for attaching the closure to the jar and subjecting the sealing ring to compression in so doing, the flange engaging the sealing ring on the inner periphery with the adjacent inclined wall engaging it on the upper face, the other inclined 45 wall of the closure engaging the ring on the outer periphery as the latter is compressed.

HORACE V. WILLIAMS.
